UNITED STATES PATENT OFFICE.

GEORGE F. McMURRY, OF EUREKA SPRINGS, ARKANSAS.

DRY CLOSET.

SPECIFICATION forming part of Letters Patent No. 340,805, dated April 27, 1886.

Application filed June 4, 1885. Serial No. 167,690. (No model.)

To all whom it may concern:

Be it known that I, GEORGE F. McMURRY, a citizen of the United States, residing at Eureka Springs, in the county of Carroll and 5 State of Arkansas, have invented a new and useful Improvement in Dry Closets, of which the following is a description.

This invention is an improvement in dry closets or commodes; and it consists in certain novel constructions and combinations of parts, as will be hereinafter described and claimed.

In the drawings, Figure 1 is a side view of my commode. Fig. 2 is a vertical section 15 thereof on a line drawn through the urine-receiver and the disinfectant-chamber. Fig. 3 is a vertical section through the body on a line at right angles to that on which Fig. 2 is cut, and Fig. 4 is a detail plan view of the 20 disinfectant-chamber with the cover raised.

The body A is formed of suitable metal, and is made in the conical shape shown, so as to provide ample space in its lower end for the excrement and facilitate the deposit of 25 disinfectant thereon. The upper open end of the body is formed or provided with an inwardly-projected concaved flange, a, to serve as a seat. This flange is usually provided with a rubber, a', or other suitable cover, which 30 serves as a cushion when the device is in use, and as a packing to prevent the exit of odors when the cover B is applied. The bottom C has a rim-flange, c, which projects up outside the body, and said bottom is secured to the 35 body by hooks D, engaging eyes d, as will be seen. I also provide the bottom with an upwardly-projecting flange, C', which extends within and close to the sides of the body A, and thus prevents the excrement from coming 40 in contact with the body; also, by pouring water in the space between the inner and outer flanges, c c', a water seal may be provided, whereby to prevent odors escaping at the lower end of the device. In winter spirits 45 may be used instead of water. The bottom may be made of pottery, stone, or earthenware, instead of metal. By the flaring shape of the body excrement deposited thereinto will drop onto the bottom and not touch the 50 sides, and the bottom will consequently be the only part to clean. This flaring of the body

also serves to provide a broader base on which to rest the body.

To the body, near its upper end, I fix the disinfectant-chamber E, which is provided with 55 a tightly-fitting cover, e, and communicates near its bottom with the body through the wide opening e'.

Within the chamber E, close above the opening e', I arrange a partition, E', through which, 60 near its inner edge, I form an opening, e''. The discharger F is located and operates below the partition E', and has a vertical wing, f, and a horizontal receiving-plate, f', extended inwardly from the lower end of the wing f. This 65 discharger is also provided with an outwardly-projected stem-handle, f'', on which I place a coil-spring, g, which holds the discharger out normally with the wing f in front of, and the plate f' below, the opening e''. 70

In operation a portion of the disinfectant passes through opening e'' onto plate f'. When excrement is deposited in the body, the user, by pressing on stem f'', will, by wing f, throw the disinfectant onto the excrement, as will 75 be seen. By contracting the body near its upper end the disinfectant may be arranged more nearly over the bottom, and a better distribution of the disinfectant will be secured. The vertical wing f serves to give the disinfectant a throw into the body, as will be seen. 80

The body A is usually provided with a suitable bail, a'', by which it may be conveniently carried.

On the side of the body A opposite the 85 chamber E, I secure the urine-receiver H, which is preferably formed on one side to fit snugly against the body A. This receiver is attached to the body by hooks h, engaging eyes h' on such body, and has a suitable tightly-fitting cover, h'', and a bail, h'', by which it 90 may be carried when detached from the body.

The urinal I is made in the segmental shape shown, so it will only project partially under the opening in the upper end of the body and receive the urine, while the excrement will 95 pass into the bottom. The object in thus separating the urine and the excrement is, that thereby decomposition does not take place so rapidly, the excrement will dry out sooner, 100 and may be more thoroughly and effectually deodorized by the disinfectant. I support this

urinal by a lug, *i*, projected inwardly from the body, and the outer wall or edge of said urinal fits up under the inwardly-inclined flange *a*, so such urinal may be conveniently removed 5 when desired. The urinal inclines toward one end, at which it has a discharge-pipe, *i'*, which passes into a discharge-opening, *i''*, in the side of the body. The outer end of this opening is surrounded by a threaded or other suitable 10 nipple, *r*, to which is attached the pipe *J*, which connects the body with the urine-receiver. I prefer to connect the pipe *J* with the urine-receiver through the lid of the latter, as thereby the urine passes directly into the receiver, 15 and does not back up into the pipe, as would be the case when the receiver was partially filled, if the attachment were made at one side of the vessel.

It will be noticed that the urinal, urine-receiver, and bottom can be conveniently detached for the purpose of emptying and cleansing such parts. The joints between the pipe *J* and the body and the urine-receiver are made air-tight by suitable packing-rings.

25 In manufacturing my device I propose to construct it of strong tin, sheet-iron, or zinc, so it will be light and may be conveniently carried from room to room.

The invention will be found particularly 30 useful in hospitals, prisons, and private dwellings.

For convenience I fix a hook or hooks, *K*, to the body *A*, on which papers may be secured.

Having thus described my invention, what 35 I claim as new is—

1. A dry closet comprising a bottomless body, an imperforate base-piece or bottom having a seat for the body, and provided with an annular flange extended upward within said body, forming a protector, and fastenings 40 whereby said body and bottom may be detachably connected, substantially as set forth.

2. In a commode, the combination, with the body provided with an inwardly-projected and downwardly-inclined flange, *a*, and a lug, *i*, 45 arranged in said body below said flange, of the segmental urinal rested on the lug *i*, and having its rear wall fitted up under the flange *a*, substantially as set forth.

3. The combination, with the body and the 50 chamber *E*, communicating with the body *A* through an opening, *e'*, and having a partition, *E'*, provided with an opening, *e''*, of the discharger *F*, located below said partition *E'*, and having a vertical wing, *f*, and a receiving- 55 plate, *f'*, substantially as set forth.

4. In a dry closet, the combination of the imperforate base-piece or bottom, the bottomless body seated at its lower end on the bottom, and the flanges *c* *c'*, secured to the bottom and projected upwardly above and on opposite sides of the lower edge of the body, the flange *c'* being extended to form a protector, substantially as set forth.

GEORGE F. McMURRY.
